UNITED STATES PATENT OFFICE

156,327

CASE FOR CARRYING MILK BOTTLES
AND THE LIKEErnest R. Erickson, Des Moines, Iowa, assignor
to C. E. Erickson Company, Inc., Des Moines,
Iowa, a corporation of Iowa

Application November 29, 1948, Serial No. 149,871

Term of patent 14 years

(Cl. D58—13)

To all whom it may concern:

Be it known that I, Ernest R. Erickson, a citizen of the United States, and a resident of Des Moines, in the county of Polk and State of Iowa, have invented a certain new, original, and ornamental Design for a Case for Carrying Milk Bottles and the like, of which the following is a specification, reference being had to the accompanying drawing, forming a part thereof.

This application is a continuation-in-part of my copending application Serial No. D. 134,962, filed November 20, 1946, now abandoned.

Figure 1 is a perspective view of a case for carrying milk bottles and the like, showing my new design.

Figure 2 is an end elevational view thereof.

Figure 3 is a side elevational view thereof, and Figure 4 is a plan view thereof.

I claim:

The ornamental design for a case for carrying milk bottles and the like, substantially as shown.
ERNEST R. ERICKSON.
